UNITED STATES PATENT OFFICE.

EDWIN E. DARRAGH, OF NEW YORK, N. Y.

DISPLAY BOX.

Application filed December 8, 1922. Serial No. 605,560.

To all whom it may concern:

Be it known that I, EDWIN E. DARRAGH, a citizen of the United States, residing at New York city, county of New York, and 5 State of New York, have invented certain new and useful Improvements in Display Boxes, fully described and represented in the following specification and the accompanying drawings, forming a part of the 10 same.

This invention relates to improvements in display boxes of that class in which the box, when opened to display its contents, is supported in inclined position on a socalled 15 easel beneath the box, formed usually as a part of the box, and an advertising or display card is provided on the top of the box which is turned upward in an erect position at the upper end of the box. The object of the invention is to provide an improved form of easel which may be readily attached to boxes of ordinary construction, and further to provide such an easel which 20 will co-operate with the box end to hold 25 the advertising or display card in erect position, when the box is opened to exhibit its contents. The invention aims to so form 30 and proportion the easel parts with respect to the box end and advertising or display 35 card that the easel, when in operative position under the box, will exert a pull on the advertising or display card and thereby hold 40 it erect, without the provision of a special support for that purpose.

To enable others skilled in the art to understand the invention, preferred and modified forms of embodiments thereof will now be described in detail in connection with the accompanying drawings, and the features forming the invention then be specifically pointed out in the claims.

In the drawings—

Figure 1 is a plan view of a blank for a preferred form of easel;

45 Figure 2 is a perspective view of a box with the cover partially broken away to show the easel in position of non-use;

Figure 3 is a partial view showing the easel in position of use;

50 Figure 4 is a section on the line 4—4 of Fig. 3;

Figure 5 is a side elevation and partial central section of a modified form of easel and its attachment to a box;

55 Figure 6 is a central longitudinal section showing the easel of Fig. 5 folded up;

Figure 7 is a section on the line 7—7 of Fig. 5;

Figure 8 is a section on the line 8—8 of Fig. 7;

Figure 9 is an end elevation of the box and easel of Fig. 5, looking in the direction of the arrow of the latter figure;

Figure 10 is a perspective view of still another modified form of easel, and

Figure 11 is an end elevation of a box showing the easel of Fig. 10 attached to the display card thereof and with the box in section for clearness.

Referring now to the drawings, and particularly to Figs. 1—4, the easel blank A (Fig. 1) is formed of the same material as the display card B, and preferably is integral therewith and with an intermediate portion or easel extension *x* connecting the display card and easel and by which they are mounted on the end, of the box. Such material preferably is comparatively thin, flexible cardboard, of approximately the same thickness as the material of which the box with which the easel is to be used, is made. The easel blank comprises side flaps *a*, *a* which are cut away as shown to form locking tabs *b*, *b* arranged to engage slits *c*, *c* when the parts *a*, *a*, *b*, *b*, and the portion in which slits *c*, *c* are formed are all folded on the lines *d* in the same direction and until they are at right angles to the body of the blank, and with the tabs *b*, *b* turned in at right angles to the flaps *a*, *a*. This will form the easel shown in Figs. 2, 3 and 4. It will be seen that this easel is trough-like in form with the two flaps *a* forming the ends of the trough and connecting the two trough sides. When the easel is in position under the box the sides of the trough act as the top and end walls of the easel, and the end walls of the trough formed by the flaps *a* act as the side walls of the easel. If the parts are properly proportioned the size of the easel will be slightly larger than the box end so that it may be folded thereover as shown in Fig. 2.

In attaching the easel to the box C, the advertising or display card B is inserted between the overlapping end flaps *e*, *e* of the box, and an inner end wall *e'* of the box. As shown, the flaps *e*, *e* are formed by extending the side walls of the box, and the end wall *e'* by an extension of the bottom of the box. A locking tab *f* formed on the easel blank is arranged to cooperate with

the top edge of the wall e' to support the display card at the top of the box and act as an abutment against downward pull on the display card. The length of the intermediate portion H relatively to the box end is slightly shorter than the height of the box end so that turning the easel under the box puts this portion under tension resisted by the engagement of the tab f with the top of the wall e' . If the parts are properly proportioned with respect to the size of the box end, the turning down of the easel will give a pull on the display card B , such pull resulting, also, in making the tab f abut more firmly against the top edge of the wall e' and thus cause the display card B to remain erect, as shown in Fig. 4. The easel and display card B will be enclosed within the cover W when the easel is folded over the end of the box.

Figures 5-9 show a modified form of easel and a different manner of attaching the easel to a box. This modification, also, is intended to embody the feature of aiding in maintaining an erect position of the advertising or display card, in that the easel is so formed and secured to the box that there will be a downward pull on the display card similar to that described above with reference to Figs. 1-4. The easel formation of the present modification is such that it may also be folded into small compass readily accommodated within the box lid or cover, and may be secured to the box before or after filling or shipment. The present easel comprises a strip of cardboard of a width approximately that of the box with which the easel is to be used and of sufficient length to form a display or advertising card B of proper size to receive the indicia desired and with enough surplus to be folded into an easel D of triangular shape in cross-section, the end of the strip being glued at o to preserve such triangular shape. The portion of the strip intermediate the display card B and the easel blank, which is preferably formed integrally with the card B , is slightly less in height than the height of the end of the box to which the device is to be attached. Centrally in the transverse fold lines k there are formed oppositely disposed locking tabs m arranged to engage slits p formed in an elongated box bottom r , such elongated bottom strip being arranged to fold up and over the end flaps s and engage a locking tab t formed in the bottom wall of the box. Thus, the easel and display card may be securely attached on the outside of the end of the box before or after shipment or filling by inserting the tabs m into the slits p . If the easel is attached before shipment or filling, a transverse fold line q may be formed in the side v of the triangular easel, so that the easel may be

collapsed, as shown in Fig. 6, and thus be readily held in such collapsed state by the cover W of the box. It will be obvious that, in the present modification, when the easel is positioned under the box, as shown in Fig. 5, the weight of the box and contents will cause a downward pull on the display card B , and that the tab m on such card B , being inserted in the slit p on the top edge of the end of the box, will force the display card to remain erect.

In Figs. 10 and 11 there is shown still another form of easel which may be readily attached to those boxes in which the advertising or display card is formed as a part of the box itself. In this modification, the easel E is made up in any suitable manner, such, for example, as the easel of Figs. 1-4, the display card, however, being omitted and a locking tongue y formed on an extension z of the easel blank being arranged to enter a slit in the display card B , as shown in Fig. 11. An easel construction such as here shown will, when attached to the display card, hold the latter in erect position, and the easel may readily be folded over the end of the box, as in the case of the easel of Figs. 1-4. The function of the easel pulling on the display card and thereby holding the latter erect is also present in connection with the present modification, and further description thereof is therefore unnecessary.

It will be seen from the foregoing that in all the forms shown the following important advantages are secured. The cover of the box, having no display card forming a part thereof, may be formed of cheap material so that it may be thrown away by the dealer when the box is to be displayed, and the box is stronger because of the cover being complete and neither the box nor cover being weakened by side cuts, as when a portion of the cover or box forms the easel. The operation of the easel is simple, and all the dealer has to do is to remove the cover, turn the easel down under the box and lift the display card. The latter cannot fall after adjustment of the easel, due to the pull of the latter on the display card, as above explained. The device, furthermore, is easy to assemble and attach to the box. In the preferred forms shown in Figs. 1 to 4, and 10, 11, also, the easel is strong, in that the side walls thereof are solid and extend all the way up to the box bottom from the base.

It will be understood that various changes in the forms of the parts above described may be made while still retaining the invention defined by the claims.

What is claimed is:

1. The combination with a box, of a display card pivotally supported at the top of the box, and an easel support slidably

5 mounted on one end of said box and secured to said display card, said easel being pivoted at the bottom edge of the box and when in operative position acting to support the box in an inclined position and exert a downward pull on said display card tending to hold the same erect.

2. The combination with a box and its cover, of a display card pivotally supported 10 at the top of the box, and a foldable easel support slidably mounted on one end of said box and secured to said display card, said easel being pivoted at the bottom edge of the box and when in operative position acting 15 to support the box in an inclined position and exert a downward pull on the display card tending to hold said card erect and when in inoperative position being foldable on the end of the box so as to be enclosed 20 within the cover.

3. The combination with a box, of a combined display card and easel support slidably mounted on one end of said box, said easel being pivoted at the bottom edge of 25 the box and when in operative position acting to support the box in an inclined position and exert a downward pull on said display card tending to hold the same erect.

4. The combination with a box, of an 30 easel support and a display card secured thereto, said easel being slidably mounted on one end of said box between the end flaps thereof, and said easel when in operative position acting to support the box in an inclined position and exert a downward pull on said display card tending to hold the same erect.

5. The combination with a box, of a combined display card and easel support, and 40 means formed on the box and easel for slidably mounting said parts on the box end, said display card being pivotally supported at the top of the box and said easel when in operative position acting to support the box 45 in an inclined position and exert a downward pull on said display card tending to hold said display card erect.

6. The combination with a box, of an 50 easel formed separately from the box and having a top wall and an end wall and side walls connecting said top and end walls and having an extension attached to the rear end of the box by being held between box layers on said end of the box, said easel 55 having its top wall pivoting directly on said extension at the bottom of the box to fold over the rear end of the box and be enclosed by a cover.

7. The combination with a box, of an 60 easel formed separately from the box and having a top wall and an end wall and side walls connecting said top and end walls and having an extension attached to the rear end of the box by being held between box 65 layers on said end of the box, said easel hav-

ing its top wall pivoting directly on said extension at the bottom of the box to fold over the rear end of the box and said extension supporting a swinging display card on the top of the box.

8. The combination with a box, of an easel formed separately from the box and having a top wall and an end wall and side walls connecting the top and end walls and separated sufficiently to provide for folding 75 the easel over the end of the box, and an extension on the easel for securing the easel on the rear end of the box, said easel having its top wall pivoting directly on said extension at the bottom of the box to fold over 80 the rear end and top of the box when not in use and to swing under the bottom of the box for supporting the latter in display position.

9. The combination with a box, of an 85 easel formed from a blank separate from the box, said blank forming an extension on the easel by which it is secured on the rear end of the box, and said blank having side flaps folding to form side walls of the easel, the top wall of said easel pivoting directly on said extension at the bottom of the box to fold over the end and top of the box when not in use and to swing under the bottom of the box for supporting the latter 90 in display position.

10. A display box having a trough-like 95 easel support provided with two walls forming the sides of the trough and two walls forming the ends of the trough and hinged by one of said trough sides directly to a lower edge of the rear end of the box and adapted alternately to be disposed beneath the bottom of said box or to fold over 100 said box end and the adjacent top portion of the box.

11. A display box having an end of multiple thickness and a trough-like easel support provided with two walls forming the sides of the trough and two walls forming the ends of the trough and pivoted at the bottom of the rear end of the box to an extension of one of the trough sides extending between the thicknesses of the box end and adapted alternately to be disposed beneath the bottom of the box or to fit over 110 the adjacent upper edge of said end.

12. A display box having an end of multiple thickness and a trough-like support 115 provided with two walls forming the sides of the trough and two walls forming the ends of the trough and pivoted at the bottom of the rear end of the box directly to an extension of one of the trough sides extending between the thicknesses of the box end and adapted alternately to be disposed beneath the bottom of the box or to fit over 120 the adjacent upper edge of said box, said extension supporting a display card 125 at the upper edge of said box end.

13. A display box having an end wall, a separate auxiliary member having a display card and easel support to project above and below the box when the latter is in use flaps extending from the sides of the box adapted to be folded over said extension to 30 confine the same and to form an outer end wall of the box.
- 5 for display and having an intermediate portion slidably mounted on the end wall of the box, said display card and easel support being foldable relative to said intermediate portion to lie closely assembled with the 10 box.
14. A display box having a double end wall, an auxiliary member having an intermediate portion extending between the elements of said wall, a display card at one 15 end of said portion and an easel portion at the other comprising parts bent to form an easel structure foldable without dismantling to nest with the body of the box, and means on said member engaging the box 20 to hold the display card against downward movement.
15. A display box having an inner end wall, a display card adapted to fold about the upper edge of said wall and having 25 an extension adapted to be applied to and over said wall, said wall and extension having tongue-engaging means preventing downward movement of the extension, and flaps extending from the sides of the box adapted to be folded over said extension to 30 confine the same and to form an outer end wall of the box.
16. A combined easel and display card blank having the easel portion A with side flaps *a* and tabs folding to form an end wall 35 of the easel and locking to hold the flaps folded to form side walls of the easel, display card B, and an intermediate portion for securing the easel to the end of the box, said easel pivoting on said extension to fold over the end and top of the box when not in use and to swing under the bottom of the box for supporting the latter in display position.
17. A combined easel and display card 40 blank having the easel portion A with side flaps *a* and tabs folding to form an end wall of the easel and locking to hold the flaps folded to form side walls of the easel, display card B, intermediate portion for 45 securing the easel to the end of the box, and tab *f* at the junction of the intermediate portion and display card.
- In testimony whereof, I have hereunto set my hand.
- EDWIN E. DARRAGH.
